GARAGE HEATER FOR AUTOMOBILES

William J. Handley, Jackson, Mich.

Application September 8, 1931, Serial No. 561,554

11 Claims. (Cl. 219—38)

This invention relates to a garage heater for automobiles, and has to do particularly with a simple, easily operated, and compactly designed electric heater.

5 The desirability of providing a heater to be placed directly underneath the crank case of the motor vehicle whereby the heat radiated therefrom will maintain the crank case oil, the transmission grease, and the various parts of the vaporizing system at the correct temperature for efficient starting and immediate operation, is well recognized in my Patent No. 1,529,885 of March 17, 1925.

10 The present invention relates to an improved heater adapted to perform much the same functions as the heater disclosed in the above mentioned patent but in a much more efficient and safe manner. In fact, one of the most important features of the present invention is the provision of an electric heater unit which is absolutely safe.

15 Another feature of the present invention resides in the novel shape of the heater whereby the motor vehicle will always be in such a position that the heat radiated from the unit will produce the most efficient results.

20 Other features reside in details of construction and general arrangement as will be more clearly brought out in the specification and claims.

25 In the drawings:

Fig. 1 is an elevation showing the heater in operative position.

Fig. 2 is a top plan view of the heater.

Fig. 3 is a section taken along the line 3—3 of

30 Fig. 2.

Fig. 4 is a section along the line 4—4 of Fig. 3.

Fig. 5 is a fragmentary detail of the heat creating unit.

35 My heater unit may be said to consist of two main parts, one part being the heat creating and transmitting part and the other part consisting of what may be generally called a ramp which makes possible the positive positioning of the unit relative to the vehicle. The heat creating unit is comprised of a cylindrical shell 1 mounted upon a stamped metal base 2 having the up-turned annular flange 3. The cylindrical shell supports the circular heat deflector 4 which has a plurality of supporting lugs 5 provided with shoulder portions 6 which engage the upper edge of the shell 1.

40 The deflector 4 is provided with the off-set portion 7 for clamping the shell 1 between the base plate 2 and the deflector 4 by means of a bolt 8. The threaded end of the bolt 8 is arranged to

receive a nut 9, which is concealed by a name plate 10 which is secured thereto by the screws 11. The deflector plate 4 makes it impossible for any inflammable material to enter the cylindrical shell 1. The lower portion of the cylindrical shell 1 is provided with a plurality of openings 12 for directing the cold air into the lower portion of the heater unit.

45 The cylindrical shell 1 is enclosed by an annular member 13, the surface 14 of which is arcuate in cross section so as to form a ramp completely surrounding and enclosing the cylindrical shell 1 which contains the heat creating unit.

The ramp 13 is provided adjacent the bottom thereof with a plurality of air openings 15, and an annular flange 16 having a plurality of openings 17 adapted to receive any suitable means for securing the heater to the floor of the garage if desired. The ramp 13 is bolted to the annular flange 3 of the base member 2 by the bolts 18.

50 It will be understood that this ramp 13 may be given various shapes, the main point being that the ramp has an inclined surface so that if any of the wheels of the automobile should strike the heater unit they will be deflected to one side thereof with the result that even if one wheel should be positioned closely adjacent the heater, the central heating unit within the shell 1 will still be positioned so that sufficient heat

55 will strike the bottom of the car as to make sure of efficient heating of the proper points thereof. The lower portion of the shell 1 has fixed thereto the L-brackets 19 which support the inner cylindrical shell 20 which is in spaced relation with the outer shell 1 and insulated therefrom by any suitable insulator such as the asbestos fiber 21. The inner cylindrical shell 20 carries a plurality of upper spokes 22 and lower spokes 23. The spokes and the cylindrical shell 22 are preferably an integral flat stamping which is rolled into the form of a spoked cylinder. Each of the spokes has a pair of inwardly turned flanges 24 forming, in conjunction with the spokes, a U-shaped channel for the reception of an insulating plate 25 for each pair of upper and lower spokes. The inner ends of the spokes 22 and 23 (Figs. 3 and 5) have struck therefrom the lugs 26 leaving the openings 27, the lugs being arranged about a central hub 28 which surrounds the bolt 8. The heating unit consists of a plurality of convolute resistance coils 29 which are supported by, and passed through, the insulating plates 25, whereby the insulating plates 25 completely insulate the resistance coils from the rest of the heating unit.

60 65 70 75 80 85 90 95 100 105 110 While the top plate 4 is so designed as to pre-

vent any gasoline from entering the heat creating member, I have made the unit absolutely safe from the danger of fire or explosion by providing a resistance unit so designed as to create sufficient heat but to remain at a temperature lower than the ignition temperature of gasoline. Gasoline, under ideal conditions, will ignite at about 750° F. while the maximum temperature inside my heater unit is designed to be around 650° F. 16 To obtain this relatively low temperature I use a relatively large amount of wire or resistance coils 29 in combination with sufficient spacing and ample supply of air.

By spacing the relatively great number of coils, 18 as shown in Fig. 3, and by providing the air inlet passageways around the base of the heater unit, it will be seen that I have provided a relatively great amount of air and a free circulation of air 20 in and around the resistance coils. The resistance units may thus be termed "black" units because they will be maintained below the glow point by the great circulation of air. While a certain predetermined amount of current is supplied to the resistance units, such units are so 25 spaced and of such relatively great body and sufficient air is supplied that the unit is maintained as a "black" unit so that even if gasoline should accidentally enter into the heater chamber it would not become ignited, even if it was 30 under ideal conditions for combustion. I have found with my unit that if the air is cut down appreciably the temperature inside of the shell 20 rises to approximately 1400° F. and while I can obtain efficient results by maintaining the 35 heater at such temperature, I obtain equally as good results by using a sufficient and free circulation of air to maintain a low temperature.

The resistance units 29, may of course, vary 40 with different constructions and different conditions and may be wired as to permit at least two separate heats. Suitable wires 30 connect the resistance units with a conveniently located switch 31 which may be operated to cut in all or 45 part of the resistance units so that a certain amount of heat may be radiated, say if the temperature is about 15° F., above zero, and another amount of heat radiated in case the temperature is liable to run below this point. I have found that in using my resistance units which operate 50 with no glow that I can supply and direct sufficient warm air to various parts of the car at correct temperatures for efficient and immediate operation and still keep the cost of operation to an average of from four to five dollars a month, figuring that the car is left in the garage only on 55 an average of twelve hours a day.

The ramp 13, not only insures that the car will be correctly positioned above the heater, but also 60 protects the heater unit and makes it possible to hang the heater on the wall in the summer time or mount it permanently to the floor. The apertures 12, circumferentially spaced around the bottom of the ramp 13, supply sufficient air to the space above the plate 2. In this way the cool air, around the bottom of the automobile and directly adjacent the floor, is taken into the bottom of the heater, heated, and directed upwardly against the bottom parts of the automobile.

The entire heater unit may be relatively small both as to circumference and height. I have found that very efficient results can be obtained from a heater unit of the type illustrated having an over all height of approximately six and one-half inches and an over all diameter of approxi-

mately eighteen inches. The height of the heater is, of course, limited by the height of the front axle 32 above the floor, or in some cases, the height of the differential but the overall diameter and/or the diameter of the heater unit 1 may vary 80 considerably.

It will thus be seen that I have provided an efficient heating unit wherein all wiring is within the ramp and all connections are maintained permanent. The use of a ramp completely surrounding the heating unit not only protects the same but also insures that the heating unit is always so positioned between the wheels of the automobile and the heating chamber supplied with sufficient air so as to give efficient results. Furthermore, the heat creating unit itself is so 85 designed and protected as to prevent all fire hazards and to give efficient results. The heater, of course, will only operate during the time that the car is in the garage and during such cold 90 weather as might affect the operation of the car. The heat from the unit will, of course, directly affect the water circulating system and will keep the oil in the crank case, the grease in the transmission, and the fuel conducting and vaporizing 100 conduits at the correct temperature for easy starting and immediate operation.

The localization of the correct amount of heat is positive and permanent and the use of my electric resistance unit makes it much cheaper 105 to heat the certain localized parts of the car than to maintain the entire garage at the same relative temperature. It will be understood that the complete heating unit will be positioned a predetermined distance from the side wall of the 110 garage and from either the front or back wall depending upon the location of the garage and the normal position in which the automobile is to stand therein; in other words, the heating unit is designed preferably to be positioned centrally 115 between the wheels of the automobile when standing in normal position and at a point just forward of the transmission housing.

What I claim is:

1. A garage heater for directing heat against 120 certain localized portions of a motor vehicle, comprising a heat radiating unit adapted to be positioned between the wheels of the vehicle, and a substantially circular ramp member substantially surrounding said heat radiating unit, said member being of less width than the wheel gage but having a sloping surface for insuring the 125 positive positioning of said heat radiating unit a predetermined distance from the inside of the wheels.

2. A garage heater for directing heat against 130 certain localized portions of a motor vehicle, comprising a heat radiating unit adapted to be positioned between the wheels of the vehicle, and a substantially circular ramp member substantially surrounding said heat radiating unit, said member being of less width than the wheel gage but having sloping surface for insuring the 135 positive positioning of said heat radiating unit a predetermined distance from the inside of the wheels, said heat radiating unit and ramp being 140 located as a single unit.

3. A garage heater for directing heat against 145 certain localized portions of a motor vehicle, comprising a heat radiating unit adapted to be positioned between the wheels of the vehicle, and a substantially circular ramp member substantially surrounding said heat radiating unit, said member being of less width than the wheel gage but having sloping surface for insuring the 150 posi-

- 55
5
relative to the normal position of the vehicle
within the garage.
- 56
5. A garage heater for localizing the applica-
tion of heat to the underside of motor vehicles,
comprising an inner cylindrical shell defining
the walls of the heat creating and radiating unit,
electric resistance means positioned within said
shell, a baffle member permitting the radiation
of heat from but preventing the entrance of any
foreign substances into said shell, and an annular
outer shell formed around said inner shell,
the exposed surfaces of said outer shell sloping to
form a ramp.
- 57
6. A garage heater for localizing the applica-
tion of heat to the underside of motor vehicles,
comprising an inner cylindrical shell defining the
walls of the heat creating and radiating unit,
electric resistance means positioned within said
shell, a baffle member permitting the radiation of
heat from but preventing the entrance of any
foreign substances into said shell, an annular
outer shell formed around said inner shell, the
exposed surfaces of said outer shell sloping to
form a ramp, a metal base for said inner and
outer shells, and air inlets at the base of said in-
ner and outer shells.
- 58
7. A garage heater for localizing the applica-
tion of heat to the underside of motor vehicles,
comprising an inner cylindrical shell defining the
walls of the heat creating and radiating unit,
electric resistance means positioned within said
shell, a baffle member permitting the radiation
of heat from but preventing the entrance of any
foreign substances into said shell, an annular
outer shell formed around said inner shell, the
exposed surfaces of said outer shell sloping to
form a ramp, said inner shell and outer shell
being provided with apertures for the positive
circulation of air through said unit.
8. A garage heater for localizing the applica-
tion of heat to the underside of motor vehicles,
comprising an inner cylindrical shell defining the
walls of the heat creating and radiating unit,
electric resistance means positioned adjacent the
bottom of said shell, a baffle member permitting
the radiation of heat from but preventing the en-
trance of any foreign substances into said shell,
an annular outer shell formed around said inner
shell, the exposed surfaces of said outer shell
sloping to form a ramp, an air chamber between
the resistance unit and the bottom of the shell,
and means arranged in combination with said
shell and resistance means for permitting circu-
lation of air through said air chamber whereby to
insulate the bottom of the unit.
9. A warm air unit for localizing the applica-
tion of heat to the underside of motor vehicles,
comprising an electrical resistance unit and en-
closing means having apertures arranged for per-
mitting circulation of air through said unit, the
amount of air circulated through said resistance
unit being sufficient to maintain the temperature
at a point below the ignition temperature of gas-
oline.
10. A warm air heating unit for localizing the
application of heat to the underside of motor ve-
hicles, comprising an electrical resistance unit
having a relatively large number of coils, and en-
closing means having apertures for supplying and
permitting circulation of a relatively large
amount of air through the resistance unit, the
vehicle being heated by a relatively large amount
of air at a relatively low temperature and the
supply of air being sufficient to maintain the
coils of said resistance unit below the glow point.
11. A warm air heating unit for localizing the
application of heat to the underside of motor ve-
hicles, comprising an electrical resistance unit
having a relatively large number of coils and en-
closing means having apertures for supplying and
permitting circulation of a relatively large
amount of air through the resistance unit, the
vehicle being heated by a relatively large
amount of air at a relatively low temperature and
the supply of air being sufficient to maintain the
temperature adjacent said unit below 750° F.
